UNITED STATES PATENT OFFICE

165,672

CONTROL KNOB FOR GAS STOVE OR SIMILAR ARTICLE

Donald E. Stewart, Grand Rapids, Mich., assignor
to Winters & Crampton Corporation, Grand-
ville, Mich., a corporation of Michigan

Application March 21, 1951, Serial No. 14,572

Term of patent 7 years

(Cl. D81—25)

To all whom it may concern:

Be it known that I, Donald E. Stewart, a citizen of the United States, residing at Grand Rapids, in the county of Kent and State of Michigan, have invented a new, original, and ornamental Design for Control Knob for Gas Stove or Similar Article, of which the following is a specification, reference being had to the accompanying drawing, forming a part thereof.

Fig. 1 is a front perspective view of a control knob for gas stove embodying my new design;

Fig. 2 is a front elevational view of the knob shown in Fig. 1;

Fig. 3 is a side elevational view thereof,

Fig. 4 is a top view of the knob, and

Fig. 5 is a rear elevational view thereof.

I claim:

The ornamental design for a control knob for gas stove or similar article, substantially as shown.

DONALD E. STEWART.
